[57] CLAIM

The ornamental design for a convertible stroller and backpack infant carrier, as shown and described.

DESCRIPTION

FIG. 1 is a left side view of a convertible stroller showing my new design in the stroller configuration;

FIG. 2 is a front view thereof;

FIG. 3 is a rear view thereof;

FIG. 4 is a top plan view thereof;

FIG. 5 is a bottom plan view thereof; and,

FIG. 6 is a right side elevation view thereof in the backpack configuration.

The broken lines in FIG. 6 show the backpack on the back of the user. The right side elevation view of the stroller configuration of FIGS. 1-5 is omitted as being a mirror image of FIG. 1.
